UNITED STATES PATENT OFFICE

EDWARD F. TERRY, JR., OF DENVER, COLORADO, ASSIGNOR TO GARDNER-DENVER COMPANY, OF DENVER, COLORADO, A CORPORATION OF DELAWARE

FLUID-OPERATED TOOL

Application filed October 26, 1928. Serial No. 315,286.

The present invention relates to tools of the type in which a hammer piston is employed and an automatic valve for controlling the distribution of the fluid to the piston.

5 One of the objects is to provide a novel structure that is exceedingly compact without enlarged protuberances on the cylinder or barrel, and in which the length of the tool is reduced over that of the ordinary tool.

10 It is now common practice to introduce lubricant for the tool into the motive fluid prior to its introduction into the tool. It has been found that under some circumstances this lubricant will accumulate in the 15 valve mechanism, usually located at the rear end of the tool and that consequently the chuck structure and associated parts do not get their share.

A further and important object is to so 20 locate the valve mechanism that a more equitable disposition of the lubricant throughout the tool is insured.

In the accompanying drawings:

Figure 1 is a view in elevation of the preferred embodiment of the invention.

Figure 2 is a longitudinal sectional view on the line 2--2 of Figure 1.

Figure 3 is a cross sectional view on the line 3--3 of Figure 2.

30 Figure 4 is a detail cross sectional view on the line 4--4 of Figure 2.

Figure 5 is a front elevation of the rear end wall disk.

Figure 6 is a rear elevation of the same.

35 Figure 7 is a sectional view on the line 7--7 of Figure 5.

Figure 8 is a detail sectional view on the line 8--8 of Figure 2.

40 Figures 9 and 10 are longitudinal sectional views diagrammatic in character and illustrating the different positions of the distributing valve and piston during the operation of the tool.

Figure 11 is a detail view of the distributing valve and indicating the form of its surfaces.

In the embodiment disclosed, a cylinder member is employed, preferably in the form of an open-ended barrel 12 having an internal 50 annular shoulder 13 in its rear end portion.

In said end portion and abutting the said shoulder 13 is a rear end wall disk 14. Fitting into the rear end wall of the barrel 12 and in rear of said disk 14 is a rear head 15. Between this rear head and the disk 14 is a ratchet ring 16 and in the inner end of said head 15 is an annular groove 17. The rear head has also formed therein a valve chamber 18, containing the usual rotary throttle valve 19, said valve controlling the supply of motive fluid to the tool and said fluid passing through the valve chamber 18 by means of a port 20 to the annular groove 17.

The ring 16 has located therein the ratchet head 21 of a rifle bar 22 that extends through the disk 14 and into the barrel. The ratchet head 21 is provided with spring-pressed pawls 23 cooperating with the teeth 24 of a ratchet ring formed by the inner end of the head 15. The rear side of the end wall disk 14 is provided with a circular groove 25 that is in communication with the groove 17 of the rear head through the space between the ratchet head 21 of the rifle bar 22 and the ring 16, so that motive fluid may flow freely to said groove 25.

At the front end of the barrel is a chuck structure. This preferably comprises the following elements. A bushing 26 is fitted into the front end of the barrel and has a flange 27 abutting against the end of the barrel. Abutting against said flange is a housing 28 in which is a rotary chuck member 29. This member receives the lugged shank 30 of a steel or other tool that is turned upon the rotation of the chuck 29, as is well understood. In front of said chuck 29 is a retaining collar 31 located in the housing 28. A chuck driver sleeve 32, suitably interlocked with the chuck 29, extends rearwardly into the bushing 26 and is provided in its rear end with a nut 33.

The rear end of the bushing 26 and the end wall disk 14 form between them in the barrel 12 a piston chamber 34. In this chamber is a reciprocating hammer piston 35 having a hammer extension 36 slidably interfitted with the nut 33 of the driver sleeve 32 and adapted to hammer upon the rear end of the drill shank 30. This piston is chambered at 100

37 to receive the rifle bar 22, said rifle bar being slidably interfitted in the usual manner with a nut 38 located in the rear end of the piston 35.

5 The rear end portion of the bushing 26 is provided with an annular external groove 39 preferably provided on its bottom with an annular rib 40. The barrel 12 constitutes an outer wall for this groove, and said groove in the 10 present embodiment constitutes a distributing valve chamber. The walls of the barrel are provided on opposite sides with spaced outstanding longitudinally disposed ribs 41, 42, 43, and 44, and the space between these ribs 15 constitutes seats for the side rods or bolts 45 that tie together the various parts by engaging the housing 28 and the rear head 15. Two 20 of these ribs, as 41 and 43 have therein passageways 46 that extend from the rear groove 25 of the end wall disk 14 to said groove or distributing valve chamber 39 and thus motive fluid can freely enter said chamber 39. Extending from said valve chamber 39 is a 25 distributing passageway 47 formed in one of the other ribs, as 44, and said passageway opens into an annular chamber 48 formed in the inner side of the end wall disk 14. Thus motive fluid can flow from the distributing valve chamber 39 to the rear end of the piston chamber 34. The other rib 42 has a distributing 30 passageway 49 opening from the valve chamber 39 at a point spaced from the passageway 47 and said passageway 49 opens into the front portion of the piston chamber 34. Said piston chamber has between its ends an 35 exhaust port 50 open to atmosphere.

40 The distribution of motive fluid is controlled by a transversely disposed automatic oscillatory and arcuate valve designated generally by the reference number 51. This valve is held in place by a pin 52 passing through its center, the opening 53 for the pin being shaped to permit said valve to rock. The valve is substantially in the form of a 45 crescent with its opposite horns or wings tapering and the end portions thereof adapted to respectively move to and from positions over the ends of the passageways 47 and 49 to alternately close the same. The valve has the inner face, as 54, of one horn and the outer face, as 55, of the other horn or wing struck from a common axis, as indicated in Figure 11, and likewise the inner face 56 of said other horn or wing and the outer face 57 of 50 the first-mentioned horn or wing are struck on the same axis, but differently located from the axis of the other described surfaces. The formation is such that the inner faces 54 and 56 correspond to the curvature of the rib 40 formed on the bottom of the chamber 39, said valve being wider than said rib as shown in Figures 9 and 10, so that the motive fluid can gain access behind the wings thereof. The outer surfaces 55 and 57 of the wings 55 of the valve correspond in curvature to the

curvature of the inner surfaces of the barrel and consequently fit snugly against the same, so as to definitely close the passageways 47 and 49.

5 The operation of the apparatus is substantially as follows. Motive fluid, suitably charged with vaporized oil, will enter the rear end of the tool and pass by way of the groove 17, chamber 25 and passageways 46, to the distributing valve chamber or groove 39. Assuming the piston 35 in a position to open the exhaust port 50 to one end of the piston chamber 34, the motive fluid will flow through either one of the passageways 47 or 49, and thus cause the valve to rock to close said passageway, as for instance 47 in Figure 3. The other passageway 49 is thus opened and consequently the motive fluid will flow through said passageway 49 into the front end of the piston chamber 34, as indicated in Figure 9, thereby driving the piston rearwardly. On its rearward movement the piston 35 will close the exhaust 50 and thereupon begin to build up pressure behind it and compress the fluid. This compression will extend through the passageway 47 so that by the time the piston approaches the rear end of its stroke a sufficient pressure will be built up upon the wing 54 of the valve to rock said valve from the position shown in Figure 3 to a reverse position. The result is that the passageway 49 to the front end of the piston chamber now becomes closed and the passageway 47 to the rear end of the piston chamber is opened. Thereupon motive fluid will flow from the valve chamber 39 through said passageway 47 into the rear end of the piston chamber and drive the piston forwardly. On this movement pressure is built up in the front end of the piston chamber 34 after the exhaust port 50 is closed by the piston and by the time the piston reaches the front end of its stroke, a sufficient pressure is built up in the passageway 49 to rock the valve back to the position shown in Figure 11, whereupon a repetition of the above described operation will take place.

105 By housing the valve in the chuck structure, the overall length of the tool is materially reduced and furthermore there are no enlargements of great size on the exterior of the barrel, the ribs 43 and 44 being relatively small and forming seats between them for the side bolts. An exceedingly compact structure is thus provided. Further than this, it will be noted that as the automatic valve constitutes a device that to a measurable extent takes out the oil from the motive fluid, this extraction takes place adjacent to the chuck structure and a sufficient part of said oil is carried into the front end of the piston chamber 34 through the passageway 49, thereby insuring a distribution of the oil through the chuck structure, making a more equable 110 115 120 125 130

distribution of the lubricant throughout the tool.

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any of the advantages of the invention.

What I claim is:

1. A fluid operated tool including a cylinder barrel, a bushing fitted into one end of the barrel and having a valve chamber, a tool chuck fitted into the bushing, a piston in the barrel having a hammer extension that operates in the bushing and on a tool placed in the chuck, and an automatic valve in the chamber for distributing motive fluid to the barrel to operate the piston.

2. A fluid operated tool including a cylinder barrel, a bushing fitted into one end of the barrel, and having an external chamber within and housed by the barrel, a tool chuck fitted into the bushing, a piston in the barrel that operates in the bushing and on a tool placed in the chuck, and an automatic valve in the chamber of the bushing for distributing motive fluid to the barrel to operate the piston.

3. A fluid operated tool including a cylinder barrel, a bushing fitted into one end of the barrel, and having a valve chamber, a tool chuck fitted into the front end of the bushing, a piston in the barrel having a hammer extension that operates in the rear end of the bushing and on a tool placed in the chuck, an automatic valve in the chuck chamber for distributing motive fluid to the barrel to operate the piston, and means connected to the rear end of the cylinder barrel and including a passageway in the barrel for directing motive fluid to the valve chamber.

4. A fluid operated tool including a barrel having spaced longitudinally disposed ribs on its opposite sides and a piston chamber, a rear head, a front chuck structure; side bolts connecting the head and chuck structure and clamping the same to the barrel and located between the ribs, a piston in the piston chamber, and means for distributing motive fluid to the piston chamber to actuate the piston including passageways formed in the ribs.

5. A fluid operated tool including a barrel having spaced longitudinally disposed ribs on its opposite sides and a piston chamber, a rear head, a front chuck structure, side bolts securing the head and chuck structure together and clamping the same to the barrel and located between the ribs, a piston in the piston chamber, an automatic distributing valve in the chuck structure, motive fluid supply passageways formed in certain of the ribs and leading to the valve, and distributing passage-

ways leading from the valve through the ribs to the ends of the piston chamber to deliver actuating fluid to the piston.

6. A fluid operated tool including a barrel having a piston chamber, a rear head for the barrel, an end wall member in the barrel at the inner end of the rear head, a chuck structure at the front end of the barrel, a piston in the piston chamber, an automatic distributing valve in the front end of the barrel, a motive fluid supply passageway extending through the end wall member and barrel to the distributing valve, and distributing passageways leading from the valve to the ends of the piston chamber, one of said passageways extending through said end wall member.

7. A fluid operated tool including a barrel having a piston chamber, a rear head for the barrel, an end wall member in the barrel at the inner end of the rear head, having grooves in its front and rear sides, a chuck structure at the front end of the barrel, a piston in the piston chamber, an automatic distributing valve in the front end of the barrel, a motive fluid supply passageway extending from the rear groove of the end wall member to the distributing valve, and distributing passageways leading from the valve to the ends of the piston chamber, one of said passageways extending to the front groove of the end wall member.

8. A fluid operated tool including a cylinder member having a piston chamber and a piston in the chamber, a distributing valve chamber partially surrounding the piston, passageways leading from the valve chamber to the end portions of the piston chamber, but in spaced relation to the end walls thereof to create compression pockets in the ends of the piston chamber, and a curved oscillatory valve located transversely of and within the cylinder member and having a pivotal mounting between its ends and having wings that alternately cover the passageways, said passageways when open directing motive fluid from the valve chamber to the piston chamber and when closed directing fluid compressed by the piston at the ends of its stroke against the wing of the valve that closes such passageway to swing the valve, open said passageway and close the other passageway.

9. A fluid operated tool including a cylinder member having a piston chamber and a reciprocating piston operating in the piston chamber, a valve chamber in the front portion of the cylinder member and extending transversely about the cylinder member and piston, an oscillatory distributing valve located longitudinally in the valve chamber, and passageways for the motive fluid between the valve chamber and piston chamber controlled by said valve.

10. A fluid operated tool including a cylinder member having a piston chamber and a

- reciprocating piston operating in the piston chamber, a fitting in the front end of the cylinder member having an annular groove forming a valve chamber, means for supplying motive fluid to the groove-chamber, distributing passageways leading from the groove-chamber to the piston chamber, and an automatic oscillatory distributing valve in the groove-chamber controlling the distributing passageways.
- 10 11. A fluid operated tool including a cylinder member having a piston chamber and a reciprocating piston operating in the piston chamber, a fitting in the front end of the cylinder member having an annular groove forming a valve chamber and extending about the piston, means for supplying motive fluid to the groove-chamber, distributing passageways leading from the groove-chamber to the piston chamber, and a substantially arcuate automatic distributing valve having a rocking mounting between its ends and having said ends controlling the distributing passageways.
- 15 12. A fluid operated tool, including a cylinder member having a piston chamber and a piston located in the piston chamber, a fitting in the cylinder member having an annular groove forming a transversely disposed valve chamber with curved inner and outer walls, means for supplying motive fluid to the valve chamber, distributing passageways leading from the valve chamber at spaced points to the end portions of the piston chamber, and
- 20 13. A fluid operated tool, including a barrel having a piston chamber, a rear head for the barrel having a fluid supply means, an end wall disk in the barrel in advance of
- 25 the rear head, and having a rear chamber connected with the fluid supply means, a chuck structure at the front end of the barrel including a bushing fitting in said barrel and having an annular groove forming a distributing valve chamber, a passageway leading from the disk chamber to the groove, distributing passageways leading from spaced points in the groove to the end portions of the piston chamber, a piston in the piston
- 30 35 40 45 50 55 60 65 chamber, and an oscillatory arcuate distributing valve having a rocker mounting in the groove between the passageways, and having its ends adapted to alternately close said passageways.
- 60 In testimony whereof, I affix my signature.
EDWARD F. TERRY, JR.
